UNITED STATES PATENT OFFICE

2,372,472

INTERNAL-COMBUSTION ENGINE

Ivan D. Campbell, Kansas City, Kans.

Application November 1, 1943, Serial No. 508,569

7 Claims.

This invention relates to improvements in internal combustion engines of the four-cycle reciprocating type and has for its principal object an internal combustion engine of the reciprocating piston type having a compressible connecting rod whereby a portion of the initial power of the explosion is stored in the compressible connecting rod and then imparted to the moving parts to drive the crank shaft.

A further object of the present invention is the provision of an internal combustion engine having a compressible connecting rod whereby the piston will travel farther on the exhaust stroke than it does on the compression stroke, thereby exhausting a larger percentage of the spent gases than is normally obtainable from the use of the fixed connecting rod.

Another object of this invention is the provision of an internal combustion engine having resilient means operable to smooth out the power stroke by distributing it more uniformly to the power stroke.

Still further objects of this invention include means whereby the motor vibration is greatly reduced and the pounding of the bearings is substantially eliminated since the sharp impact of the explosion is absorbed by the resilient or compressible connecting rod.

Other objects will appear during the course of the specification wherein reference is had to the drawing in which:

Figure 1 is an elevational view partly broken away of an internal combustion engine embodying this invention.

Fig. 2 is an enlarged elevational view partly in section of the compressible connecting rod including a portion of the associated parts.

Fig. 3 is a sectional view taken on line III—III of Fig. 2.

Fig. 4 is a sectional view taken on line IV—IV of Fig. 2.

Throughout the several views like reference characters refer to similar parts, and the numeral 10 designates a crank case of an internal combustion engine in which is rotatably mounted a crank shaft 12 of the usual type wherein crank offsets 14 with crank pin 16 are provided for each cylinder and are relatively offset circumferentially to present a substantially even flow of power to said crank shaft.

A cylinder block 18 of any standard make is carried by the crank case 10 and is provided with a cylinder 20 in which is reciprocably mounted a piston 22. Conventional inlet valve 24 and exhaust valve 26 are provided to admit the fuel gas

and exhaust the spent gases. Spark plug 28 is timed in the usual manner to ignite the fuel gas at the end of the compression stroke.

The connecting rod 30 comprises a member 32 having a head 34 which clampingly engages the piston pin 36 and also having a stem 38 which extends into the cylindrical recess 40 formed in the connecting rod member 42 having a head 44 which is operatively connected with the crank pin 46 by means of the bearing cap 48 and screws 50. The cylindrical recess 40 has an enlarged portion 52 adjacent its outer end to form an abutment 54. A cylindrical disc 56 is fitted into the enlarged portion 52 of the cylinder to rest on abutment 54 and is secured in position by a set screw 58. Stem 38 is slidably mounted in disc 56 and is threaded at its outer end at 60 to receive a guide piston 62. Set screw 64 serves to prevent accidental unscrewing of the piston. Normally, disc 56 and guide piston 62 are spaced apart a sufficient distance to receive a coil spring 66 therebetween. This coil spring is inserted under compression and serves to urge piston 62 further into the cylindrical recess 40.

25 A helical spring 68 encompasses stem 38 with its one end resting against head 32 and the other end thereof resting against the centering disc 56. It will be noted that the lower portion of helical spring 68 is positioned in the upper portion of the recess 52. Spring 68 as shown in Fig. 2, is substantially at its normal length and is adapted to be compressed to such a degree that the adjacent convolutions will contact each other, thereby providing a limit to the shortening of the connecting rod. The coil spring 66 is relatively light but always exerts a sufficient force on guide piston 62 to maintain the head 34 against the spring 68 to preclude all lost motion of the parts.

40 Any conventional lubricating system, such as the one shown, wherein the oil is delivered to the crank pin by an oil scoop 70 through hole 72, thence through hole 74 to the cylinder recess 40, thence by way of a center opening 76 formed in

45 stem 38 to the piston pin 36 may be used. The reciprocating action of the guide piston 62 as hereinafter described will cause a pulsating action of the oil to force it against gravity to the desired points.

50 The action of the engine is best described by referring to Fig. 1 and considering that the piston 22 and the associated parts are at the early stage of the power stroke. As is the usual practice, the ignition of the compressed fuel gas is provided when the connecting rod is in substantial align-

ment with the center of the piston pin and the center of the crank shaft. The crank shaft rotates in the direction indicated by the arrow and is usually traveling at a high rate of speed, thus producing a peak pressure against the piston when the connecting rod is substantially positioned as shown in Fig. 1. This explosion stroke exerts a driving force against the crank pin 16 and at the same time compresses the helical spring 68. As the piston 22 moves farther downwardly in cylinder 20 and the explosion pressure is reduced, the stored up energy in spring 68 will be imparted to the crank pin as the connecting rod returns to its normal position. This application of the power stroke makes it possible to apply the driving power to the crank shaft when the leverage relation of the parts is substantially at its maximum.

On the exhaust stroke, when valve 26 is open and there is very little head pressure, the piston will travel farther in the cylinder than it will during the compression stroke when all valves are closed and the fuel gases are highly compressed. This action of the piston is made possible by the helical spring 68 and has the advantage of discharging a larger percentage of the spent gases than could be obtained by the use of the standard connecting rod. This spring action also absorbs and stores up to a considerable degree, the sharp explosive force of the fuel explosion, thus reducing the wear of the engine bearings, reducing the engine vibration and producing a much smoother action of the power stroke.

While this compressible connecting rod has been shown on a four-cycled reciprocating internal combustion engine, yet it is thought possible that it might be adapted for use with various other types of internal combustion engines. Furthermore, slight changes might be made in the connecting rod per se without departing from the spirit of this invention.

What I claim as new and desire to be secured by Letters Patent is:

1. In an engine of the class described having a reciprocable piston and a rotatable crank shaft, a longitudinally compressible connecting rod disposed between said piston and crank shaft and operatively connecting said piston and crank shaft and resilient means to limit extension of said connecting rod.

2. In an engine of the class described having a reciprocable piston and a rotatable crank shaft, an extensible connecting rod having an expandable spring which normally holds it in the extended position when operatively connecting said piston and crank shaft, and a relatively weak spring disposed to constantly compress said extension spring.

3. In an engine of the class described having a reciprocable piston and a rotatable crank shaft, an extensible connecting rod normally held in the extended position by a relatively strong expandable spring normally urged to the contracted position by a relatively weak spring when operatively interconnecting said piston and crank shaft.

4. In an engine of the class described having a reciprocable piston and a rotatable crank shaft, an extensible connecting rod having one of its end portions slidably mounted in a recess in the other end portion of said connecting rod, a spring mounted on said rod to urge said rod portions in opposite directions, and a spring mounted on said rod piston to constantly urge said connecting rod parts to the contracted position.

5. In an engine of the class described having a reciprocable piston and a rotatable crank shaft, an extensible connecting rod having one of its end portions slidably mounted in a recess formed in the other end portion of said connecting rod,

20 a spring mounted on said rod to urge said rod portions in opposite directions, and resilient means to limit the relative outward movement of said connecting rod portions.

6. In an engine of the class described having a reciprocable piston and a rotatable crank shaft, an extensible connecting rod having resilient means whereby it may be forcefully extended or shortened from its normal position operatively connecting said piston and crank shaft whereby 25 the piston is permitted to travel different lengths of stroke during the operation of the engine.

7. In an internal combustion engine having a reciprocating piston and rotatable crank shaft, an extensible connecting rod interconnecting said piston and crank shaft and having resilient means whereby it is normally maintained at a predetermined extended length, and resilient means operable to limit its extension.

50 IVAN D. CAMPBELL.
